UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE TRANSMISSION SYSTEM.

Application filed November 25, 1919. Serial No. 340,480.

To all whom it may concern:

Be it known that I, RAY S. WILBUR, a citizen of the United States, residing at Lyndhurst, in the county of Bergen, State of New Jersey, have invented certain new and useful Improvements in Telephone Transmission Systems, of which the following is a full, clear, concise, and exact description.

10 This invention relates to improvements in telephone systems, and has particular reference to the four-wire repeater circuit therefor.

15 In transmission lines, it is common to provide amplifying means for reinforcing currents of low frequency, such as employed in signaling between operators or subscribers. It is also desirable to impress upon a metallic circuit, simultaneously with the transmission of ringing current, other signaling current such as employed for the Morse code.

20 It has been customary, in four-wire repeater circuits, when transmitting ringing current, for instance, from a terminating circuit over an outgoing line, to operate an electromagnetic device for the purpose of supplying ringing current to said line. The operation of this device opens and unbalances the outgoing line while ringing current is being applied and thereby prevents the transmission of metallic Morse signaling current.

25 An object of this invention is to prevent unbalancing of the outgoing circuit when applying ringing current thereto, whereby other signaling current may be impressed upon the line or metallic side of said circuit simultaneously with said ringing current.

30 The drawing illustrates diagrammatically a four-wire repeater circuit showing the application of the invention thereto.

35 In the drawing, A designates an incoming line, B a terminating circuit and C an outgoing line. Ringing current transmitted over the incoming line A is induced into the secondary winding of the repeating coil 1, from thence to the back contacts and upper and middle armatures of relay 2, the back contacts and armatures of relay 3, and then to the primary winding of the repeating coil 4. A low frequency filter consisting of condensers 5 and a bridged inductance 6 is employed to filter out ringing and voice currents below a certain range of frequency so that all ringing current will be diverted

40 to the primary winding of the repeating coil 4, as before stated. This ringing current is then induced into the secondary winding of the repeating coil 4, which is in circuit with battery and the filament and grid of a repeater 7. The current is here amplified in the usual manner and a relay 8 tuned to respond to this amplified current is energized. This causes the energization of relay 9 which is made slow to release so that the 45 same will remain energized during any momentary deenergization of relay 8 due to a decrease in the amplification of the current passing through the winding thereof. Energization of relay 9 connects a source of ring- 50 70 current 10, preferably of $16\frac{2}{3}$ cycle frequency, to the terminating circuit B, through the middle and lower armatures and front contacts of relay 9, resistances of auto-transformer 11 and primary windings of the 55 three-winding transformer 12. The attraction of the upper armature of relay 9 closes a bridge across the line A, through resistance 13 and thus prevents unbalancing of the line. Voice currents within the usual 60 range of frequency will pass from one line to another through the normal contacts of relays 2, 3 and 9 after the latter relay has released its armatures at the termination of the application of ringing current to the 65 circuit B.

70 Ringing current of the usual $16\frac{2}{3}$ cycle frequency transmitted from the terminating circuit B passes to the middle points of the three-winding transformer 12, the auto-transformer 11, normal contacts of the middle and lower armatures of relay 9 and the windings of the ringing response relay 14. This relay is responsive to the ringing current and, by its energization, opens the energizing circuit of relay 15 which releases its 75 armature. A circuit is then closed from grounded battery, through the windings of relays 2 and 3 in parallel, and the armature and contact of relay 15, to ground. Relays 2 and 3 are energized. Relay 2, by attracting its armatures, disconnects the incoming line A and bridges said line through resistance 16, to prevent unbalancing of the line during the application of ringing current. Relays 2 and 3 connect ringing current, preferably of a frequency of 133 cycles, from a source 17 through alternate contacts of said relays, and from thence to the windings of a transformer 18 which is connected 80 85 90 95 100 105 110

to the output side of the three-winding transformer 12, between the secondary windings thereof and on either side of the condenser therein. The ringing current is transmitted from the secondary windings of the three-winding transformer, over the sides of the outgoing line C, through the repeating coil 19. Inasmuch as line C is not opened during the transmission of ringing current thereover, as is apparent from the foregoing, the line will remain balanced or continuous to permit of the application of other signaling current thereto, while said ringing current is being applied. Voice currents will be transmitted from circuit B directly through the primary and secondary windings of three-winding transformer 12 to the line C.

The advantage of the feature just mentioned, of not opening line C during the transmission of ringing current thereover will be apparent if we consider that line C in addition to being employed for transmitting speech currents is also employed for two-way metallic telegraph operation. The usual method of duplexing a two-wire line for telegraph signals is to shunt the line by a suitable bridge 30, connections therefrom being taken to the usual telegraph relay and balancing network. This balancing network is, of course, adapted to match the impedance of the line as seen from leads 32 and 33, which would be the combined impedance of outgoing line C and the impedance looking in the direction of line B whereby the local receiving equipment will not be actuated by the outgoing telegraph signals. It would, therefore, follow that if in applying the ringing currents from generator 17 to outgoing line C, the line C were temporarily opened, the impedance of the system connected to leads 32 and 33 would be changed, thereby unbalancing the telegraph equipment and preventing the successful duplex operation thereof.

What is claimed is:

1. In a telephone system, a two-wire circuit, a four-wire circuit, a three-limb transformer for coupling one side of said four-wire circuit to said two-wire circuit, a source of ringing currents, and means responsive to ringing currents in said two-wire circuit for impressing currents from said source upon said side of said four-wire circuit while maintaining fixed the connections of said side to said transformer.

2. In combination, a local station comprising terminals of a terminating circuit, terminals of an outgoing line, an artificial balancing line for said circuit, a three-winding transformer having a winding in said circuit, a winding in said balancing line and a third winding in said outgoing line, a local generator of ringing currents, and means responsive to ringing currents from

a distant station for impressing ringing currents from said generator upon the midpoints of the first two windings of said transformer to transmit said currents to said terminating circuit.

3. A signaling station, a plurality of lines terminating at said station, a network for balancing one of said lines, a three-winding transformer having a winding in circuit with said first line, a second winding in circuit with said balancing network and a third winding in circuit with a second line, a third line being connected to the midpoints of said first two windings, a local generator of ringing currents, and means responsive to ringing currents in said third line for impressing ringing currents upon the midpoints of said first two windings.

4. In combination, a signaling station, a four-wire circuit and a two-wire circuit terminating at said station, said station comprising means for coupling said circuits, a source of ringing currents, and means responsive to ringing currents in said two-wire circuit for disconnecting one side of said four-wire circuit from said coupling means and for impressing ringing currents from said source upon the other side of said four-wire circuit.

5. A telephone signaling station, a four-wire circuit and a two-wire circuit terminating at said station, means for coupling said circuits, means in one side of said four-wire circuit for preventing ringing currents from the said one side of said four-wire circuit from being impressed directly upon said two-wire circuit, a plurality of sources of ringing current, means comprising movable contacts in the said one side of said four-wire circuit and responsive to ringing currents in said two-wire circuit for connecting one of said sources to the other side of said four-wire circuit, and means comprising movable contacts in the said one side of said four-wire circuit and responsive to ringing currents in said four-wire circuit for connecting another of said sources to said two-wire circuit.

6. A telephone signaling station, a two-wire circuit and a four-wire circuit terminating in said station, said station comprising means for coupling said circuits, a plurality of movable contacts included in the speech transmission path of one side of said four-wire circuit, means responsive to ringing current originating in said two-wire circuit for operating certain of said contacts, and means responsive to ringing current originating in one side of said four-wire circuit for operating other of said contacts.

7. In combination, a three-winding transformer, a line in circuit with one winding of said transformer, a balancing network for said line in circuit with a second wind-

ing of said transformer, a second line in circuit with the third winding of said transformer, a second transformer having a winding in circuit with said second line, 5 a source of signaling currents, and means responsive to signaling currents in said first line for connecting said source to said second transformer.

8. A signaling station, a four-wire circuit 10 and a two-wire circuit terminating at said station, connections coupling both sides of said four-wire circuit to said two-wire circuit, said connections being traversed by ringing currents from said two-wire circuit, 15 a local source of ringing currents, and means responsive to ringing currents in said two-wire circuit for impressing ringing currents from said source upon one side of said four-wire circuit while maintaining 20 fixed the connections of the said one side to said two-wire circuit.

9. In combination, a three-winding transformer, a line connected in circuit with one winding of said transformer, a balancing 25 network for said line in circuit with the second winding of said transformer, a second line in circuit with the third winding of said transformer, a third line connected to the midpoints of said first two windings, 30 a local source of signaling currents, and means responsive to signaling currents originating in said first line for impressing currents from said source upon one of said other lines while maintaining fixed the connection of said last-mentioned line to said transformer.

10. In combination, a line for the transmission of signals of one type in either direction, a second line for the transmission 40 of signals of one type in one direction only, a signaling station comprising means for coupling said lines, movable contacts in said second line, means controlled by currents in said first line for controlling certain of said contacts, and means controlled by currents in said second line for controlling other of said contacts.

11. In combination, a line for the transmission of signals of one type in either direction, a second line for the transmission of signals of one type in one direction only, a signaling station comprising coupling 50 means for said lines, and means comprising movable members responsive to signaling currents from said first line for impressing signaling currents upon said second line

while maintaining fixed the connections of said second line to said coupling means.

12. In combination, a line for the transmission of signals of one type in either direction, a second line for the transmission of signals of one type in one direction only, 60 a signaling station comprising means for coupling said lines, a local source of ringing currents, and means responsive to ringing currents in said first line for impressing ringing currents from said source upon said second line while maintaining fixed the connections of said second line to said coupling means. 65

13. In combination, a two-wire line, a four-wire line, means for coupling said lines, a source of signaling currents, a local network having an impedance approximating the impedance of one side of said four-wire lines, and means responsive to signaling currents in said two-wire line for applying signaling currents from said source to one side of said four-wire line, for breaking 75 the connections between said coupling means and the other side of said four-wire line, and for connecting to said network that part of said broken side away from said coupling means.

14. In combination, a two-wire line, a four-wire line, coupling means for said lines, a source of signaling currents, a local network having an impedance approximating the impedance of one side of said four-wire line, and means responsive to signaling currents in one side of said four-wire line for applying signaling currents from said source to said two-wire line, for breaking 80 the connections between said coupling means and the said one side of said four-wire line, and for connecting said network to the part of said broken side located away from said coupling means. 85

15. In a telephone system, a two-wire circuit, a four-wire circuit, means coupling 95 one side of said four-wire circuit to said two-wire circuit, a source of ringing currents, and means responsive to ringing currents in said two-wire circuit for impressing currents from said source upon said 100 side of said four-wire circuit while maintaining fixed the connections of said side to said two-wire circuit. 105

In witness whereof, I hereunto subscribe my name this 21st day of November A. D. 110 1919.

RAY S. WILBUR.
